UNITED STATES PATENT OFFICE

2,177,367

IMPULSE COUNTER AND STOP WATCH
TIMER

Paul E. Klopsteg, Chicago, Ill., assignor to Central Scientific Company, a corporation of Illinois

Original application May 16, 1929, Serial No. 363,688, now Patent No. 2,024,230, dated December 17, 1935. Divided and this application December 5, 1935, Serial No. 53,110

6 Claims. (Cl. 161—15)

This invention relates to counter and timer devices and more particularly to electrically operated impulse counter and stop watch timer devices.

- 5 One of the objects of the invention is the provision of new and improved mechanism for indicating the number of electrical impulses energizing an electric circuit in a predetermined period of time.
- 10 A further object of the invention is the provision of a new and improved device for indicating electrical impulses in electric circuits especially adapted to be used by students in experimental work in school and college laboratories
- 15 and the like.

A still further object of the invention is the provision of a new and improved apparatus for simultaneously indicating intervals of time and the number of electrical impulses energizing an electric circuit by the operation of an electrically operated timer device.

Another object of the invention is the provision of a new and improved electrically operated impulse counter and stop watch timer that is simple in construction, inexpensive to manufacture, easily assembled, composed of few moving parts and that is efficient and accurate in operation.

Other and further objects and advantages of the invention will appear from the description 30 taken in connection with the accompanying drawings, in which—

Fig. 1 is a diagram illustrating the application of the fundamental principles to a moment of inertia machine, inclined plane and horizontal plane acceleration and velocity devices, and an Atwood machine for determining the law of falling bodies together with an impulse counter and stop watch timer device constituting the subject matter of this invention;

40 Fig. 2 is a horizontal section on line 2—2 of Fig. 3;

Fig. 3 is a vertical section on line 3—3 of Fig. 2; and

Fig. 4 is a plan view of the cover of the impulse 45 counter.

In the study of displacement and acceleration of masses under the laws and forces governing the same, especially in experimental work conducted by trained experimenters as well as by 50 students in schools and colleges, it is highly desirable that the apparatus be accurate and that the experimental data be obtained in a minimum amount of time and effort. The present invention is designed more particularly for use in this 55 relation.

Referring now to the application there is disclosed one embodiment of the invention which is by way of example only.

A general organization showing the use of the device in connection with experimental apparatus is illustrated in Fig. 1 in which is shown a source of current represented by the battery A, a spark timer indicated generally by B, which opens the primary circuit of a spark coil, indicated generally by C, the secondary of which delivers sparks to a record receiver associated with a moment of inertia machine, generally indicated by D, an inclined plane acceleration device, indicated generally by E, a horizontal plane velocity device, indicated generally by F, and an Atwood 10 machine for determining the laws for falling bodies, indicated generally by G, and associated with the spark timer B, is the impulse counter and stop watch device, generally indicated by H. The device may be employed with one or more 15 of the different apparatus shown, or may be associated with all as illustrated.

This application is a division of my application, Serial No. 363,688, filed May 16, 1929, Patent No. 2,024,230, of December 17, 1935.

Referring now more particularly to Figs. 2, 3 and 4 there is shown a base 116 equipped with a metal stamping 117 provided with upturned arms 118, 119, 120. The arm 118 carries the coils 121 of an electro-magnet which are connected with 20 binding posts 122 carried by the base 116.

The armature 123 is mounted to rock on pivot bearings 124, carried by the arms 119, and is constantly urged to the right in Fig. 3, by a spring 125 adjustably connected at 126 to the arm 120, 30 which also carries an adjustable stop 127 for limiting the rotation of the armature away from the magnet.

The armature is equipped with an arm 128, carrying a driving pawl 129, adapted to cooperate with a ratchet 130, fixed to a shaft 131, journaled in the hollow post 132, made fast to the stamping 117 and the base 116. A post 133 (Fig. 5) on the base 116 carries a holding pawl 134 and a stop finger 135 for the driving pawl 129.

The binding posts 122, which are suitably insulated from each other, may be inserted in the wire connection 57 of Fig. 1, or may be substituted for the binding posts of the primary of the spark coil C. In either case, the windings 121 will be intermittently energized, and cooperate with the spring 125 to give the armature a 50 rocking motion.

As the armature rocks to the left in Figs. 2 and 3, the curved end 136 of the pawl 129 drives 55

the ratchet counter-clockwise until the curved end strikes the stop finger 135, which checks the motion of the pawl, and, therefore, the armature, and also locks the pawl to the ratchet to prevent 5 the latter overrunning. Each oscillation of the armature will, therefore, move the ratchet one tooth, and the pawl 134 will hold the ratchet while the armature rocks to the right.

The shaft 131 is equipped with a needle or 10 pointer 137 (Fig. 4) running over a suitable scale 138, carried by the casing 139, and visible through the crystal 140.

The shaft 131 is also equipped with a pinion 141 meshing with a gear 142 on a shaft 143 journaled in a hollow column 144 fixed to the base 116. The shaft 143 is also equipped with a shorter needle, or pointer 145 running over a smaller scale 146, also visible through the crystal 140.

A lever 147 fulcrumed at 148 on the bottom of 20 the base 116 has a wedge or cam 149 adapted to control the armature by engagement with the arm 150 thereon which projects downwardly through a slot in the base. The end of the lever 147 opposite to the wedge 149 is pivoted to a push 25 rod 151 loosely in the base 116 and normally held in a raised position by a spring 125, against the free end of a leaf spring 152; and this rod 151 is equipped with a finger piece 163 at a convenient height above the base.

30 The invention may be employed in numerous relations and with various types of devices. In Fig. 1 is shown the application of the invention to several different devices which will illustrate its wide range of use and adaptability.

35 The spark coil or transformer C is provided with a primary winding indicated at 54, is in circuit with the spark timer B, which in turn is in circuit through the conductors 51, 53, 55, 57, etc., with a source of electrical energy such as a battery A. The timer comprises electromagnets 46, a vibrator or armature 22 supported at 14 and operating between adjustable contact points 29 and 30, shown diagrammatically in Fig. 1, the secondary of this coil having the leads 87 and 88. Suitable switches or contacts 87e, 87f, 87g or 87h, shown diagrammatically in Fig. 1 are employed for closing the secondary or sparking circuit through the coil or transformer C.

An incline plane accelerator device is shown at E and comprises an incline track 92 along which a massive roller 91 is adapted to travel. The roller is journaled as at 93, in a frame 94. A sensitized strip or record receiving member 96 is attached to the frame as at 95, and passes over 55 a pulley 87 mounted on a bracket 98 at the upper end of the track 92. A light weight 99, attached to the lower end of the strip 96, insures the proper travel of the strip over the pulley.

The conductor 88 is electrically connected with 60 the pulley 87 over which the strip 96 travels, and spark point device 115 which is electrically connected to the switch. Contact 87g is arranged adjacent to the pulley so that when the switch S is moved to engage the contact 87g, the electrical 65 impulse caused by the vibration of the member 22 will cause sparks to pass from 115 through the strip into the pulley, thereby recording along the sensitized strip the impulses as the same pass over the pulley as the weight 91 rolls down the track.

A horizontal plane or velocity device, is shown at F and comprises a horizontal track 104, along which a mass 100, supported by anti-frictional 70 rolls 103 is adapted to move under the influence of weight 109 which is attached at one end of a

sensitized strip 106, the other end of which is connected to the mass as at 105.

The strip 106 passes over roll 107 journaled to bracket 108 at the outer end of the track 104. The mass may be varied by removable weights 5 102, which are adapted to engage support 101 on the mass 100.

The lead 88 of the transformer or coil C is in electrical connection with the pulley 107 and switch 87f is in connection with the spark device 115 which operates the roll 107. The weight is adapted to move the mass 100 along the track and simultaneously the sparking device 115 will deliver sparks which are controlled by the vibrating bar 22 to the record receiving strip 106. 15

An inertia device is shown at D and comprises a rotating mass 73 having a circular periphery 65 on which the record receiving member may be secured. The rotating mass is in electrical connection with the secondary coil of the transformer by the lead 88 and a sparking device 115 opens the periphery of the rotating masses in electrical connection with the switch 87h through the conductor 87'. When the device is in the position shown in Fig. 1, with the switch S in engagement with the contact 87h, sparks will be delivered to the sensitized strip or sheet during the rotation of the mass.

An Atwood machine is shown at G and comprises a pulley 111 over which a sensitized record 30 receiving strip or band formed in a loop, is adapted to travel. This strip or band is provided at different points with balancing weights 112 and 113, one of which is augmented by the addition of a driving weight 114. The weight 114, under the 35 influence of gravity, will cause the strip to travel over the roller and a sparking device 115 will deliver sparks through the same, which are controlled by the operation of the vibrating bar 22.

In the operation of the device in connection 40 with the operation of the Atwood machine, for example, a sensitized record strip 110 is placed on the pulley 111 and the balancing weights 112, 113 and the driving weight 114 are applied. After the indicators 137 and 145 of the impulse 45 counter and watch timer are set, the circuit is closed and the driving weight released. From the number of impressions made on the record strip in a given length of time as indicated by the device, the distances between the impressions 50 noted and corrections made for friction, etc., the laws of falling bodies may be experimentally determined. The operation of the impulse counter and stop watch timer is similar when used with the other devices, A, D and E and need not 55 be here repeated.

In all these experiments compensation for friction 60 can readily be made by applying weight to the system until uniform motion ensues, obtaining a spark record, reducing it to numerical data 65 by suitable measurements and making a corresponding correction on the other charts made.

The period of time corresponding to a chart record, including any number of sparks is best ascertained by the spark timer B. 65

For any given adjustment of the spark timer, the impulse counter must be rated with some standard such as a stop watch or the second hand of any timepiece. This may be accomplished by releasing the controller of the impulse counter as 70 the second hand passes a selected position and stopping it when the hand passes another selected position several minutes later.

A skillful operator can stop the impulse counter at zero on the scale, and anyone can set it at 75

zero by using the control lever to rock the armature manually until the pointer arrives at zero.

With either of the connections suggested, the magnet of the impulse counter is energized for each spark and, therefore, gives a readily visible indication either actually or substantially at the same instant.

The impulse counter enables the student, with the aid of a stop watch, to accurately determine for himself the time corresponding to a selected number of vibrations or spark intervals, which is important, both because the interval is a squared quantity in all acceleration formulae, and because the student is not asked to accept this basic quantity on faith.

When the spark timer and the impulse counter have been rated with a stop watch, they become a high-speed electrical stop watch useful wherever short intervals are to be measured.

It is thought from the foregoing taken in connection with the accompanying drawings that the construction and operation of my device will be apparent to those skilled in the art and that changes in size, shape, proportion and details of construction may be made without departing from the spirit and scope of the appended claims.

I claim as my invention:

1. In an impulse counter, a base, a pair of sleeves rigidly mounted on said base and extending upwardly therefrom, an electro-magnet, means for energizing the same, an armature for said magnet, an indicator shaft journaled in one of said sleeves, a ratchet wheel on said shaft, a pawl on said armature for operating said ratchet, an indicator hand on the upper end of said shaft, a scale beneath said hand, a pinion on said shaft, a second shaft journaled in the other of said sleeves, a gear on said second shaft in mesh with said pinion, a pointer on the upper end of said second shaft, and manually operated means for stopping the movements of said hand and pointer while said electro-magnet is being energized and deenergized.

2. In an electrically operated impulse counter and stop watch timer, a pair of dials, a pair of indicators movable around said dials, mechanism including an electro-magnet for causing said indicators to move around said dial in timed relation, an armature, means for pivotally mounting said armature adjacent to said magnet, an arm on said armature, a spring for normally retaining said armature out of contact with said magnet, and means comprising a pivoted lever having a push rod on one end and a cam surface on the other for engaging said arm for moving the armature into engagement with said magnet when said push rod is operated.

3. In apparatus of the class described, an im-

pulse counter including an indicator and means for automatically continuously operating the indicator at equal intervals of time including a ratchet, holding and driving pawls cooperating with the ratchet, an armature for operating the driving pawl, said armature having an extension thereon, a magnet for moving the armature, and means including a single lever member having a cam on one end for engaging said extension for stopping the operation of said impulse counter at any time during its operation and for resetting said indicator.

4. An apparatus of the class described comprising a pair of pointers, a scale beneath each pointer, a gear and pinion for driving one shaft from the other, means including a ratchet mechanism for operating one of said pointers intermittently, an electro-magnet, a movable armature operable by said magnet for operating said ratchet mechanism, a manually operated cam for engaging said armature, and a lever for moving said cam for stopping said pointers and for resetting the same at any point desired.

5. In an impulse counter, a base, an electro-magnet mounted on said base, means for energizing the same, an armature for said magnet, an arm extending downwardly from said armature through said base, a pointer, means operated by the movement of said armature for moving said pointer, and manually controlled means including a cam member engaging said armature for stopping the movement of said armature and for resetting said pointer, said means comprising a pivoted lever beneath said base having a push rod on one end and a cam surface on the other for engaging said arm for moving the armature into engagement with said magnet when said push rod is operated.

6. An impulse counter comprising a base, a pair of elongated bearings mounted on said base and extending upwardly therefrom, a shaft journaled in each bearing, a pointer on each shaft, a scale beneath each pointer, an intermeshing gear and pinion on said shafts, a ratchet on one of said shafts, an electromagnet on said base, a pivoted armature member having a portion thereof extending through an enlarged opening in said base, a resilient pawl rigidly mounted on said armature member for operating said ratchet, adjustable means for normally holding said armature member spaced from said magnet, a lever pivoted member beneath said base, a push rod extending upwardly through said base and connected to said lever, and a cam engagement between said members for forcing said armature member into engagement with said magnet when said push rod is depressed.

PAUL E. KLOPSTEG.
